UNITED STATES PATENT OFFICE.

ROBERT PIERPONT, OF NEW HAVEN, CONNECTICUT, ASSIGNOR TO J. WILLIS DOWNS, OF SAME PLACE.

DESIGN FOR A SEWING-MACHINE FRAME.

SPECIFICATION forming part of Design No. 25,585, dated June 2, 1896.

Application filed April 28, 1896. Serial No. 589,461. Term of patent 14 years.

To all whom it may concern:

Be it known that I, ROBERT PIERPONT, of New Haven, in the county of New Haven and State of Connecticut, have invented a new 5 Design for Sewing-Machine Frames; and I do hereby declare the following, when taken in connection with the accompanying drawings and the letters of reference marked thereon, to be a full, clear, and exact description of the 10 same, and which said drawings constitute part of this specification, and represent, in—

Figure 1, a view in side elevation of my 15 newly-designed sewing-machine frame; Fig. 2, a plan view thereof with the ribbed arm broken away on the line *ab* of Fig. 1; Fig. 3, a view thereof in rear elevation.

This invention relates to a design for sewing-machine frames; and the design consists 20 in the configuration shown in the accompanying illustration and hereinafter described.

As herein shown, my newly-designed sewing-machine frame has an oblong scroll-like base *A*, the ends of which are turned inward 25 at a right angle to form feet *A' A'*. The upper corners of the base are rounded, while the lower corners are square. Within the said base, and toward the forward edge thereof, I locate a plate *B*, the lower edge of which

is slightly concaved. From the outer end of the said base rises a four-ribbed arm *C*, the upper end of which extends forward at a right angle and terminates in a bearing-head *D*, respectively provided at its upper and lower ends with horizontally-arranged bearing-flanges *D'* and *D''*. The inner rib of the arm *C* is continued across the upper face of the base in the form of a rib *E*, which terminates at the foot of an upright *F*, to the upper end of which the work-table is secured. 35 The spool-support *G* offsets rearwardly from the upper portion of the ribbed arm *C*, while a friction-device sleeve *G* offsets from the horizontal forwardly-extending portion of the said arm. 40

Having described my newly-designed sewing-machine frame, what I claim is—

The design for sewing-machine frames shown in the accompanying illustration, and herein described. 50

In testimony whereof I have signed this specification in the presence of two subscribing witnesses.

ROBERT PIERPONT.
